tion, a corporation of Pennsylvania

Application July 15, 1950, Serial No. 11,213

Term of patent 14 years

(Cl. D26—11)

To all whom it may concern:

Be it known that we, Fritz E. Florschutz, Wayne S. Aspey and Edmund L. Izzi, citizens of the United States, residing respectively at Pittsburgh 21, Turtle Creek, and Pittsburgh 6, in the county of Allegheny and State of Pennsylvania, have invented a new, original, and ornamental Design for a Circuit Interrupter, of which the following is a specification, reference being had to the accompanying drawing, forming a part hereof.

Fig. 1 is a side-elevational view of a circuit interrupter showing our new design.

Fig. 2 is an end-elevational view.

Fig. 3 is a plan view in section taken along the line III—III of Fig. 1 looking in the direction of the arrows.

The dominant features of our design reside in the portions illustrated in the drawing in solid lines.

We claim:

The ornamental design for a circuit interrupter, substantially as shown, and described.

FRITZ E. FLORSCHUTZ.

WAYNE S. ASPEY.

EDMUND L. IZZI.
